UNITED STATES PATENT OFFICE.

HENRY L. FERRIS, OF HARVARD, ILLINOIS, ASSIGNOR TO HUNT, HELM, FERRIS & CO.,
OF HARVARD, ILLINOIS, A CORPORATION OF ILLINOIS.

FENCE-POST.

1,158,911.

Specification of Letters Patent.

Patented Nov. 2, 1915.

Application filed March 16, 1915. Serial No. 14,699.

To all whom it may concern:

Be it known that I, HENRY L. FERRIS, a citizen of the United States, residing at Harvard, in the county of McHenry and State of Illinois, have invented a new and useful Improvement in Fence-Posts, of which the following is a specification.

My invention relates to improvements in fence posts and more particularly to a form of metallic fence post, carrying means by which wire fencing may be secured thereto.

The invention will be more readily understood from the following detailed description of one form of fence post constructed in accordance therewith. In this description reference will be had to the accompanying drawings, in which—

Figure 1 is a front elevation of a fence post and a section of wire fencing supported thereby; Fig. 2 is an enlarged detailed elevation of the upper end of the fence post shown in Fig. 1; Fig. 3 is a section on the line 3 of Fig. 2; Fig. 4 is a section on the line 4 of Fig. 2; Fig. 5 is a section showing an alternative manner of forming the body of the post.

Referring more particularly to the drawings, it will be seen that the fence post shown therein is constructed as a hollow body having relatively thin walls designated 10, and in the form shown in Figs. 1 to 4 of the drawing of cylindrical shape and with the joint designated 11 lying at the back of the post. In the drawing I have shown a central butt joint unsecured, but it will be understood that a lapped, welded or crimped joint of any description might be used.

Referring to Fig. 3 it will be seen that the front base or face of the post opposite the joint 11 is provided with a plurality of projecting parts which are preferably formed by punching or pressing outwardly the material of which the post is formed. These projecting parts I have shown as arranged in a series extending lengthwise of the post and relatively close together. The specific form of projections illustrated in the drawings comprises pairs of members, each pair consisting of an out-turned tongue designated 12 and extending at a slight angle to the horizontal, and below the tongue a conoidal or inclined cylindrical piece designated 13. The tongues 12 are each perforated as shown in 14 and the bosses 13 are open at their upper ends, *i. e.*, the ends oppo-

site the tongues 12, as designated at 15 on the drawing. The specific manner of construction and manufacture by which these tongues and bosses are produced forms no part of my present invention, but it may be stated generally that they may be readily constructed by cutting, punching and pressing operations in a manner quite obvious to those skilled in this art.

In order to secure the strand-wires 16 of a wire fence to a post formed in the manner I have described the wires are brought into contact with the front face of the post to extend across the opening 17, and a securing rod may then be inserted through the perforation 14 of the tongue 12 and through the open upper end 15 of the boss 13. The strand-wire 16 thus becomes locked between the securing rod and the front base of the post, is held against vertical movement by the under face of the tongue 12 and the upper end of the boss 13, and against horizontal movement by the face of the post on one side and by the locking rod on the other side. I find it convenient to use an ordinary wire nail designated 18 as a locking rod in the preferred construction of my invention, the head of the nail seating on the top of the tongue 12 and the point of the nail facilitating its insertion in the open upper end of the boss 13.

In order to accommodate fences having various numbers and spacings of the strand-wires I prefer to form the projecting securing means at short intervals throughout the length of the post. The securing means may thus be so closely spaced as to render it possible to slightly stretch the strand-wires in the event they should lie in such a relation as to fail to register exactly with the securing means of the post.

In Fig. 5 of the drawings I have shown a fence post of a triangular cross-section, the seam 11' in this post being located at the apex of the angle opposite the front face 10' in which the projecting securing means are formed, it being quite obvious that the exact form of the post is immaterial to my invention.

A fence post constructed in the manner contemplated by my invention, as exemplified by the foregoing specific description of one construction, possesses numerous advantages both from the standpoint of manufacture and use. A primary advantage of such

a construction as that contemplated by my invention is the facility with which the wires may be secured to the post and removed therefrom when necessary. It will be noted that such securing and removal of the wires requires no deformation of the parts of the post per se, but merely the insertion or withdrawal of a locking rod. My post may, therefore, be secured to and detached from the fence wires with the greatest facility without any injury to or deterioration in the same.

While I have shown and described in considerable detail one specific embodiment of my invention it is to be understood that such showing and description is illustrative only and that I do not regard my invention as limited to these details of construction nor to any of them except in so far as such limitations have been included within the terms of the following claims, in which it is my intention to claim all novelty inherent in my invention as broadly as is possible in view of the prior art.

I claim:

1. A metallic fence post comprising a hollow body portion having a plurality of projecting tongues on one of its faces and extending in substantially horizontal relation thereto, a hollow boss formed on the face of the post adjacent each of the said tongues,

the said boss being provided with an aperture facing the said tongues and opening into the interior of the post, and a locking rod seated in the said tongue and entering the interior of the post through the aperture of the boss whereby said locking rod is secured in substantially vertical position to avoid accidental dislodgment and with the greater extent of its body portion bearing against said boss, for the purpose set forth.

2. A metallic fence post comprising a hollow body portion having a plurality of projecting tongues out-struck from one fence and extending in substantially horizontal relation thereto, each of said tongues having a perforation therein, a hollow boss out-struck from the face of the post to form a shoulder below each of the said tongues and having an open upper end opposed to the perforation in said tongue, and a headed locking bolt passing downwardly through the perforation in the tongue and entering the post through the aperture of the boss in substantially vertical position to avoid accidental dislodgment and with the greater extent of its body portion bearing against said boss, for the purpose set forth.

HENRY L. FERRIS.

In presence of—

HOWARD J. FERRIS,
CHAS. T. MINOT.
